UNITED STATES PATENT OFFICE.

PATRICK H. ROBINSON, OF RACINE, WISCONSIN, ASSIGNOR TO HAMILTON BEACH MFG. CO., OF RACINE, WISCONSIN, A CORPORATION OF WISCONSIN.

BRUSH GUARD.

Application filed September 13, 1926. Serial No. 135,120.

This invention relates to improvements in brush guards for vacuum cleaners.

Heretofore, vacuum cleaner brush guards have rested upon the lower surfaces of the suction nozzle and have thus formed an objectionable protrusion. It is one of the objects of the present invention to provide a brush guard which will be flush with the lower surfaces of the suction nozzle, and 10 which will thus in no way interfere with the operation of the cleaner.

A further object of the invention is to provide a brush guard which may be readily removed when it is desired to clean the 15 brush.

A further object is to provide a guard which will effectively prevent the rug from being drawn up into the suction nozzle during 20 operation of the cleaner.

20 A further object is to provide a brush guard which will rest in recesses formed on the lower surfaces of the suction nozzle, said recesses making it possible for the guard to be flush with the lower surfaces and also 25 serving to keep the guard in its proper place.

With the above main and other incidental objects in view, which will appear as the description proceeds, the invention consists 30 of the improved brush guard and its parts and combinations as set forth in the claims and all equivalents thereof.

In the accompanying drawing in which the same reference characters indicate the same parts in all of the views:

35 Fig. 1 is a view of the lower surface of the suction nozzle of a vacuum cleaner showing the brush guard in connection therewith;

Fig. 2 is a section taken upon the line 2—2 40 of Fig. 1;

Fig. 3 is an end view of the suction nozzle of a vacuum cleaner showing the brush guard in attachment therewith;

Fig. 4 is a plan view of the guard detached 45 from the cleaner, and

Fig. 5 is a fragmentary rear view of the suction nozzle showing portions of the brush guard resting in the recesses.

Referring more particularly to the accompanying drawing, the numeral 6 designates 50 the suction nozzle of the vacuum cleaner, said suction nozzle having recesses 7 on its

lower surface, and front and rear longitudinally extending ribs 8.

The brush guard proper comprises a longitudinal rod 9 and a plurality of U-shaped members. The U-shaped members comprise intermediate transverse portions 10, having bent end portions 11 attached to the longitudinal rod, and hook portions 12 for engaging one of the ribs 8 of the suction mouth. 55

To attach the guard, the longitudinal rod and the hook portions are snapped over the ribs 8 of the suction nozzle, and the brush guard is then moved sidewise to engage the intermediate members 10 with the recesses 7 of said suction nozzle. With the intermediate members resting in the recesses, it may readily be seen that the guard will be flush with the lower surfaces of the suction nozzle and will therefore form no hindrance to the operation of the cleaner. It will also be seen that the attachment or removal of the guard is very simple, the members 12 and 9 merely snapping over the ribs 8 of the suction nozzle. 70 75

From the foregoing description, it may be seen that the brush guard is simple in construction, strong and durable, efficient in operation, and well adapted for the purpose 80 described.

What I claim as my invention is:

1. The combination with a vacuum cleaner casing provided with a downwardly opening elongated suction nozzle formed with lower front and rear longitudinally extending ribs and with transverse recesses in its front and rear lower edges, of a removable brush guard therefor comprising a rod and a plurality of U-shaped members having their end portions attached thereto, the said guard extending around and engaging the outer front and rear portions of said ribs and extending through said recesses, the recesses being of such depth that the U-shaped members of the brush guard will lie flush with the lower edge surfaces of the suction nozzle. 90 95

2. The combination with a vacuum cleaner casing provided with a downwardly opening elongated suction nozzle formed with lower front and rear longitudinally extending ribs and with transverse recesses in its front and rear lower edges, of a removable brush guard therefor comprising a rod and a plurality 100

of U-shaped members having upwardly extending end portions attached to said rod, and having longitudinal hook portions and intermediate transverse portions, the rod and the hook portions extending upwardly and engaging the outer upper front and the upper rear portions of the ribs, and the in-

termediate transverse portions extending through the recesses, the recesses being of such depth that the lower surfaces of the brush guard will lie flush with the lower edges of the suction nozzle.

In testimony whereof, I affix my signature.
PATRICK H. ROBINSON.
